UNITED STATES PATENT OFFICE.

CHARLES W. KIRSCH, OF THREE RIVERS, MICHIGAN, ASSIGNOR TO KIRSCH MANUFACTURING COMPANY, OF THREE RIVERS, MICHIGAN, A CORPORATION OF MICHIGAN.

STAIR-CARPET FASTENER.

939,601.

Specification of Letters Patent.

Patented Nov. 9, 1909.

Application filed December 7, 1908. Serial No. 466,272.

To all whom it may concern:

Be it known that I, CHARLES W. KIRSCH, citizen of the United States, residing at Three Rivers, in the county of St. Joseph 5 and State of Michigan, have invented certain new and useful Improvements in Stair-Carpet Fasteners; and I do hereby declare the following to be a full, clear, and exact description of the invention, such as will enable others skilled in the art to which it 10 appertains to make and use the same.

My invention relates to a novel construction in a device for securing stair carpets without driving nails or tacks through the 15 said carpet, the object being to provide a simple and efficient device of this character, and consists in the features of construction and combinations of parts hereinafter fully described and claimed.

20 In the accompanying drawings illustrating this invention: Figure —1— is a front elevation of a stair carpet fastener constructed in accordance with my invention. Figs. —2— and —3— are transverse sections of 25 the same on the lines 2—2 and 3—3 respectively of Fig. —1—. Fig. —4— is a fragmentary rear elevation of the same. Fig. —5— is a fragmentary longitudinal section of the same on the line 5—5 of Fig. —4—. 30 Fig. —6— is a fragmentary vertical section of a stairway equipped with a carpet secured by means of fasteners constructed in accordance with my invention.

The objects of my invention are: First: 35 To provide a stair carpet fastener which is adjustable in length to secure carpets of various widths. Second: To provide a fastener which fits very snugly in the corner and against the carpet so as to be out of the 40 way and present a very neat appearance. Third: To provide a fastener which is easily removed and replaced without necessitating the removal and replacement of nails or tacks whereby the carpet may be easily 45 moved with sufficient frequency to distribute wear thereon. Fourth: To provide a fastener which is sufficiently stiff and durable to firmly hold the carpet in place without the use of nails or tacks and which is at the same 50 time inexpensive and easily mounted and operated.

The fastener comprises end plates A of 55 rectangular form equipped with integral flanges B, C and D, the flanges C being disposed at opposite ends of the plate A and ex-

tending at an angle of forty-five degrees thereto, said flanges being provided with openings for the passage of nails or screws by means of which the plate A is secured in the corner of the step in an obvious manner, 60 said plate being disposed at an angle of forty-five degrees to the tread and riser when secured. The flange B is triangular and extends at an incline in a direction opposite to the direction of extension of the flanges C, 65 the free end thereof extending into the corner and the side edges thereof lying in contact with the tread and riser respectively. The flange D is disposed opposite the flange B and is flush with the plate A, said flange 70 D being provided in its middle portion with an opening E. The said end plates A are mounted in opposed relation on opposite sides of the stair carpet and serve to secure the fastening strips. The latter consists of 75 two strips F and G of sheet metal each provided on its side edges with flanges H extending at an angle of forty-five degrees thereto. The strip or member F overlaps the strip or member G and is provided adjacent the overlapping end with cleats I which are bent over so that the free ends thereof engage the outer faces of the flanges H of the member G, said cleats serving to 80 telescopically connect or couple said members. Adjacent the free ends of the middle or web portions of the said members F and G are two projections J which are adapted to enter the openings E in the flanges D of the plate A to secure said strips to the latter. 85 The said cleats I consist of tongues formed by cutting U-shaped incisions in the member F in a well known manner and the projections J are formed by drawing up the metal to form a concavo-convex portion as is commonly practiced.

In operation the stair carpet is laid to pass between the plates A and is pressed into the corners formed by the meeting of treads and risers. The fastening strips are then 100 mounted in place by laying the same upon the carpet in the said corners and inserting the free end of the member F underneath the flange D of one plate A so that the projection J of said member enters the opening E 105 in said flange D. The free portion of said member is then firmly pressed into the corner with one hand and the member G then moved longitudinally until its free end passes under the flange D of the other plate A and 110

the projection J and opening E engage each other. The strip is thus firmly secured and prevents the stair carpet from being drawn out of the said corners.

5 Where stair carpets of unusual width, stiffness or weight of body are employed, it becomes necessary to employ fastening means between the ends of the fastening strip to prevent bellying of the latter. To this end 10 the member F is provided in its middle or web portion with one or more perforations K and the strip G is provided in its corresponding part with a longitudinal slot L registering with said perforations and permitting free passage of the shanks of nails or screws through the middle portion of said fastening strip.

The device is very simple and efficient, and is obviously very easily operated.

15 20 I claim as my invention:

1. A stair carpet fastener comprising fastening plates disposed on opposite sides of the carpet and secured in the corner formed by the meeting of the tread and riser, flanges 25 on said plates extending toward the carpet, and provided with openings, and longitudinally adjustable fastening strips provided at their ends with projections, said ends being adapted to pass under said flanges of said plates and said projections entering the openings in the latter.

30 2. A stair carpet fastener comprising fas-

tening plates disposed on opposite sides of the carpet and secured in the corner formed by the meeting of the tread and riser, flanges 35 on said plates extending toward the carpet, and provided with openings, and longitudinally adjustable fastening strips having flaring side flanges and provided at their ends with projections, said ends being adapted to 40 pass under said flanges of said plates and said projections entering the openings in the latter.

3. A stair carpet fastener comprising end plates provided with flanges extending at an 45 angle of forty-five degrees to said plate and ninety degrees to each other, said flanges being secured to the tread and riser of a stairway, one of said plates being disposed on either side of the carpet, end flanges on said 50 plates extending toward the carpet and having openings therein, longitudinally telescopic adjustable fastening strips passing at their ends underneath the end flanges of said plates, and projections on said ends 55 of said strips entering said openings in said end flanges.

In testimony whereof I have signed my name in the presence of two subscribing witnesses.

CHARLES W. KIRSCH.
